GRINDING FIXTURE

Paul E. Lehman, Dayton, Ohio

Application November 8, 1935, Serial No. 48,805

6 Claims. (Cl. 51—225)

My invention relates to grinding fixtures and particularly to adjustable grinding fixtures for adjustably supporting tools or cutters during the grinding or sharpening thereof.

It is an object of my invention to provide an improved adjustable grinding fixture capable of supporting different types of tools or cutters and adapted for use with any type of grinding machine, such as surface grinders, tool grinders, or a common machine with a movable table combined with an electric tool grinder.

It is a further object of my invention to provide a grinding fixture wherein the cutter or tool to be sharpened is rotatably mounted on a cutter supporting means carried by a cutter carrying member, which member is itself rotatable through an arc of 360° on an axis at right angles to the axis of the cutter supporting means.

It is a still further object of my invention to pivotally mount the cutter carrying member on an intermediate member pivotally mounted on a fixed base whereby the cutter or tool to be sharpened may be inclined at substantially any required angle during the process of sharpening or grinding thereof.

Still further objects of my invention include the provision of an indexing device carried by the tool carrying member and adjustably mounted for movement into and out of contact with the cutter to be ground; to provide certain ground surfaces on the fixture whereby a protractor or the like may be used for determining the proper angle at which the cutter is to be set; to provide an improved locking device whereby the various movable elements of the fixture may be locked in the desired position without affecting a change in such position during the locking operation; and to provide other specific improvements which will become apparent from a brief consideration of the fixture itself, a specific embodiment of which I have described in the following specification, taken in conjunction with the drawings forming a part hereof.

In the drawings:

Fig. 1 is a front elevation of my improved fixture;

Fig. 2 is a side elevation thereof; and

Fig. 3 is a view in elevation showing the three main parts of the device separated.

My improved fixture, as shown on the drawings illustrating one form thereof, consists primarily of three elements, namely a base member 10, an intermediate member 11, and a tool carrying member 12. The intermediate member 11 is pivotally mounted on the base 10 for oscillatory

movement at right angles to the longitudinal axis of the base 10. The tool carrying member 12 is pivotally mounted on the intermediate member 11 for oscillatory movement in planes parallel to the longitudinal axis of the base. Thus, with respect to the base member 10, the tool carrying member 12 is movable in a plane at right angles to the longitudinal axis of the base and is rotatable through an arc of 360 degrees in a plurality of planes parallel to the longitudinal axis 10 of the base. This movement of the tool carrying member through an arc of 360 degrees permits the grinding or sharpening of any type of milling machine cutter and particularly difficult angle cutters, by use of flat grinding surfaces.

An important feature of my invention is the means for mounting the member 12 on the intermediate member 11 and for mounting the intermediate member 11 on the base 10, and the means in conjunction therewith for locking these elements in the desired positions. To this end, intermediate member 11 includes a bifurcation consisting of the two leg portions 14 and 15 straddling the lug 13 formed in the base member 10. A ground tube or hollow shaft 16 extends through the openings 18 in the leg portions 14 and 15 and passage 19 in the lug 13. This shaft 16 constitutes a bearing on which the intermediate member 11 oscillates with respect to the base member 10, and insures an accurate movement of the intermediate member with respect to the base member 11. This tube or hollow shaft fits snugly in the openings 18 and considerable force is required to remove it therefrom. There is sufficient frictional resistance between the tube 16 and the intermediate member 11 that a slight force is required to move the member 11 with respect to the base member 10. This frictional resistance maintains the member 11 in position with relation to the base 10 during the locking operation.

To lock the member 11 in position with respect to the base 10, I have provided a bolt 17 extending loosely through the tube or hollow shaft 16 and having threaded on its end a nut 20. The purpose of this bolt 17 and nut 20 is merely to lock the intermediate member in its proper position and does not serve as a pivotal axis. This type of locking device does not disturb the accurate setting of the intermediate member with respect to the base 10, during the locking or unlocking operation.

Substantially the same construction is used for the pivotal mounting of the cutter carrying member 12 on the intermediate member 11 and for locking these members in assembled positions.

For example, the leg portions 14 and 15 of the intermediate member 11 extend upwardly and join to form lugs 21 and 22 each provided with holes 23. The cutter carrying member 12 fits between the lugs 21 and 22 and is supported for oscillatory movement in such position by means of a hollow shaft 27 passing through openings 23 and through the passage 25 formed in the member 12. This hollow shaft corresponds to the hollow shaft 16 previously referred to and constitutes a bearing for the tool holding member 12 and insures the precision movement of member 12 relative to the intermediate member 11. It fits snugly in the openings 23 and considerable force is required to remove it therefrom. There is sufficient frictional resistance between the tube 27 and the member 12 that a slight force is required to move member 12 relative to the tube 27. This frictional resistance maintains the element 12 in its selected position during the locking operation.

A bolt 24 passes through the hollow shaft 27 and together with the nut 26, serves to lock the member 12 in position with respect to the intermediate member 11. This bolt 24 fits loosely in the tube 27 and serves merely to lock members 11 and 12 in position. It may be tightened or loosened without affecting the setting of the members 11 and 12.

If desired the hollow shafts 16 and 27 may be sealed and protected from possible damage resulting from small particles of metal, grit or grinding material falling thereon by means of grease packed into and retained by the grooves 31.

The tool carrying member 12 comprises the central body portion 28 and leg portions 29 and 30 extending laterally from the body portion 28 and at right angles to each other. Each leg portion includes a means for supporting a tool, such as a cutter, to be ground or sharpened. This means comprises the ring guide member 34 integral with the leg portion 29 and surrounding a shaft 35 pressed or threaded into or even integral with leg portion 29 and having a passage 36 therein.

In the particular embodiment shown, the cutter 39, fits over the shaft 35, is rotatable thereon, and slidably engages the ring member 34, being held in position by means of a C washer 38 fitting over the bolt 40 having a head 41 larger than the slot 44 of the C washer. The bolt 40 passes through the passage 36 and on the other side of the leg portion 29 the bolt 40 is surrounded by a spring 43 having one end bearing against the leg portion 29 and its other end bearing against a washer retained by the nut 45 threaded on the bolt 43. When in position on the tool carrying member 12, the cutter 39 rotates about the shaft 35.

An important feature of my invention is the location of the axis about which the tool carrying member 12 rotates with respect to the intermediate member 11. As shown on the drawings, this axis, comprising the tube or hollow shaft 27, is located within the body portion 28 of the member 12 and substantially at the center thereof. This arrangement, in addition to providing a low center of gravity, also permits the rotation of the member 12 through an arc of 360 degrees, whereby the member 12 may be set at any required angle.

During the grinding or sharpening operation, it is desirable to limit the rotation of the cutter itself to one direction. It is also desirable to provide means for indexing or holding each tooth

of the cutter in position to be ground or sharpened. Both of these functions are performed by the leaf spring member 50 carried by the member 12 and movable therewith and adapted to engage to straight sides of the teeth to thereby act as a pawl for preventing counter-clockwise movement of the cutter and at the same time indexing each tooth to a grinding position.

This spring 50 is carried by the arm 51 removably mounted in the clamping lugs 53 through which passes the bolt 54. These lugs 53 form part of the arm 56 removably mounted on the extension 55 forming a part of the tool carrying member 12. This arrangement permits the spring 50 to be moved into and out of engagement with the cutter 39. When in position it permits rotation of the cutter in a clockwise direction due to its resiliency but prevents movement in counter-clockwise direction. As previously pointed out it likewise indexes each tooth 20 of the cutter to a proper position for grinding.

Only the one cutter supporting means, namely that formed on the lug portion 29, has been specifically described. However, a similar means indicated generally at 60 is provided, differing merely in its size for it is constructed to receive and support a cutter or tool of different size center depression.

I have also provided means whereby the proper setting of the tool holding member 12 with respect to the base 10 may easily be determined. In the particular embodiment shown, the upper surface 10 of the base member 10 is ground to present a perfectly level surface. The surface 11 of the leg portion 29 and a corresponding surface on the leg portion 30 are also ground level. By placing a protractor upon the surface 10, the member 12 can be rotated and adjusted to the desired angle without difficulty. Likewise the intermediate member 11 may similarly be moved 40 and adjusted to the proper angle.

From the above brief description of my improved adjustable cutter fixture, it will be apparent that I have provided a fixture wherein a full universal movement of the cutter is obtained, and wherein full rotary movement of the cutter carrying member 12 on its tubular axis 27 is possible. This full rotary movement provides a means whereby the cutter to be ground or sharpened may be set at any desired angle. It will also be apparent that by reason of the improved type of mounting, I can obtain very accurate movement of the movable elements with respect to one another without possibility of disturbing the accurate setting of the members during the locking or unlocking operation.

While I have described one form of my invention, other modifications coming within the scope of the appended claims, are clearly within the scope of my invention.

What I claim as new is:

1. A fixture comprising a base member, a tool carrying member and means for pivotally mounting said tool carrying member on said base, said means including a removable tubular member extending through said base member and said carrying member and a means for locking said members in the desired relative position, said locking means including a threaded bolt extending loosely through said tubular member.

2. A fixture comprising a base, a member pivotally mounted on said base, said member comprising two leg portions extending laterally of the pivotal mounting and at right angles to each other, means on each of said leg portions for

5 rotatably supporting a tool to be sharpened or ground and means carried by said member and movable into engagement with either of said tools for preventing rotational movement thereof in one direction.

6 3. A portable tool grinding fixture comprising a base, a member pivoted to said base and including a pair of spaced apart supporting lugs, a cutter supporting means pivotally mounted on 10 said member and between said lugs and mounted for full rotary movement about an axis at right angles to the axis about which said member pivots, said cutter supporting means including two leg portions extending laterally on opposite 15 sides of said pivoted mounting and at right angles to each other and means on each of said leg portions for supporting a cutter to be ground.

7 4. A portable tool grinding fixture comprising a base, a member pivoted to said base, a cutter 20 supporting means pivotally mounted on said member and mounted for full rotary movement about an axis at right angles to the axis about which said member pivots, said cutter supporting means including two leg portions extending laterally on 25 opposite sides of said pivoted mounting and at right angles to each other, means on each of said leg portions for supporting a cutter to be ground and indexing means carried by said cutter supporting means and movable into contact with 30 either of said cutters.

5. A device of the class described including a

base member, an intermediate member pivoted thereto about an axis, means for limiting the movement of said intermediate member through an arc of less than 360°, said intermediate member including a pair of spaced apart supporting lugs, a tool carrying member supported on said intermediate member between said lugs and mounted for full rotary movement through an arc of 360° on an axis extending through said lugs, said last named axis being substantially at right angles to the first mentioned axis and said axes lying in substantially parallel planes.

6. A device of the class described including a base member, an intermediate member pivoted thereto about an axis, means for limiting the movement of said intermediate member through an arc of less than 360°, said intermediate member including a pair of spaced apart supporting lugs, a tool carrying member carried by said intermediate member between said lugs and mounted for full rotary movement through an arc of 360° on an axis extending through said lugs, said last named axis being substantially at right angles to the first mentioned axis and said axes lying in substantially parallel planes, said tool carrying member including a central body portion and two leg portions extending laterally and at right angles to each other on either side of said central body portion.
